UNITED STATES PATENT OFFICE.

EDMOND W. T. RICHMOND, OF ROMFORD, ENGLAND.

DESIGN FOR A GAS-STOVE.

SPECIFICATION forming part of Design No. 33,882, dated January 8, 1901.

Application filed December 11, 1900. Serial No. 39,562. Term of patent 7 years.

To all whom it may concern:

Be it known that I, EDMOND WALTER TYRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a front elevation of a gas-stove embodying my design.

The leading features of my design are the skeleton front of the grate A, the upper front plate C, having foliated ornamentations, the arch-shaped frame D, having the beading d, and the conventionalized foliated ornamentation e and the arch-shaped border E within

the frame D, having the quatrefoil figures f and the parallel grooves g. There is also a panel H below the grate, having conventionalized leaf ornamentations, and from the opposite sides of which project upwardly ornamental figures h'. 20

I claim—

The design for a gas-stove, substantially as herein shown and described. 25

In testimony whereof I have hereunto subscribed my name.

EDMOND W. T. RICHMOND.
